UNITED STATES PATENT OFFICE.

ROBERT J. BENNETT, OF MOLINE, ILLINOIS, ASSIGNOR TO ARTISTA PIANO PLAYER COMPANY, OF MILAN, ILLINOIS, A CORPORATION OF ILLINOIS.

CONTROLLING DEVICE FOR SELF-PLAYING PIANOS.

1,030,863.

Specification of Letters Patent.

Patented July 2, 1912.

Application filed August 25, 1909. Serial No. 514,469.

To all whom it may concern:

Be it known that I, ROBERT J. BENNETT, a citizen of the United States of America, and resident of Moline, Rock Island county, 5 Illinois, have invented a certain new and useful Improvement in Controlling Devices for Self-Playing Pianos, of which the following is a specification.

My invention relates to player pianos or 10 piano players, as the case may be, and has especial reference to the levers and devices for regulating and controlling the automatic playing, as, for example, the tempo, skip key, rewind and expression mechanisms.

The object of my invention is to provide means whereby a single shifting member, such, for example, as the tempo lever, may carry with it means for controlling one or 20 more of the above described mechanisms, so that the same hand, without removing it from the said lever, may be used for in various ways exercising control over the automatic playing mechanism.

25 A further object is the provision of an improved arrangement whereby the means for regulating the above described mechanism, or some portion thereof, may be so positioned as to be entirely out of sight 30 when not in use.

A further object is the provision of a regulating or controlling device that can be cheaply constructed and least liable to get out of order.

35 These and such other objects as may hereinafter appear are attained by my invention, an embodiment of which is illustrated in the accompanying drawings, in which—

Figure 1 represents a sectional view on 40 line 1—1 of Fig. 2, looking in the direction indicated by the arrows, showing my improved device in position, the cover which serves as a tempo lever being shown raised in dotted lines. Fig. 2 is a cross-sectional view on line 2—2 in Fig. 1, looking in the direction indicated by the arrows. Fig. 3 is a sectional view on line 3—3 of Fig. 1, looking in the direction indicated by the arrows. Fig. 4 is a sectional view on line 4—4 of Fig. 1, looking in the direction indicated by the arrows.

Like numerals of reference indicate like parts in the several figures of the drawings.

Referring now to the drawings—4 represents the key-slip of a player piano hav-

ing an opening or channel 5 extending therethrough and into the key-rail 6, as shown at 7. A passage 8 communicates with the interior of the piano. At the bottom of the opening 5 and on either side of 60 the channel 7 are guides or ways 9, extending into channels or pockets 10, 11, communicating with the opening 5. Mounted within the opening 5 and seated on a base 12 is a metal block 13 provided with a plurality of pockets or channels 14, 15, 16. A pair of circular hollow pneumatic connections 17, 18, screw into the base 12, the openings or channels 19, 20, in said connections registering with the openings 15, 16, in the 70 block 13. Small air passages 17^a and 18^a through the connections 17 and 18 connect the chambers 15—19 and 16—20. A channel 21 from the atmosphere communicates with the upper chamber 22, and a pipe 23 75 connects the lower channel 19 with pneumatically operated stop or skip key mechanism (not shown). Similarly a channel 24 communicates with the upper chamber 25, and a pipe 26 connects the lower chamber 20 with pneumatically operated rewind mechanism (not shown). A pair of keys or push-buttons 27, 28, fit within pockets 29, 30, in the block 13, and terminate in valve-stems 31, 32, on which are mounted valves 33, 34, held against circular seats 35, 36, by the coil springs 37, 38, surrounding the posts 38^a which serve as a stop for the valves 33—34. When the buttons or keys 27 or 28 are pushed down, the valves 33 or 34 are 90 un-seated, admitting atmospheric air and reducing the tension in the tubes 23 or 26 and setting in operation the skip key mechanism, or the rewind mechanism.

A post or support 39 is secured to the 95 block 13 provided with upwardly projecting ears 40. A swinging cover 41 is pivotally mounted between these ears and held in closed position by means of an ordinary spring 42. One end of a second spring 43 is mounted on the plate 12 and provided with a catch or stop 44. When the end of the cover 41 is swung down, out of engagement with the spring 42, it is swung over the stop 44 pressing down the spring 43. 100 After the end passes the stop 44, the spring resumes its normal position and holds the cover 41 in upright position, as shown in dotted lines in Fig. 1. This upright cover 105 now serves as a handle or lever by means 110

of which the block 13 and all the parts mounted therein can be shifted laterally within the opening 5. This block, by means of any well-known mechanism, connects 5 with the governor or tempo mechanism, and regulates the speed of the roll by the shifting movement, serving as a tempo regulator. On the free end of the spring 43 is mounted a stud or post 45 passing through 10 the block 13 and projecting slightly above the top. By pressing down on this stud the stop 44 is pushed down below the end of the member 41, releasing it and rendering it possible to close the cover.

15 It is evident that the support 39 may be dispensed with and the cover mounted directly on the block 13; so, also, other details of construction may be modified without departing from the spirit of my invention.

20 In the operation of my invention, the cover 41 is swung downwardly until the upper end is rigidly in place, as shown in dotted lines in Fig. 1. By grasping this member between the first and second fingers of 25 the right hand, the third and fourth fingers are left free to operate the keys 27 and 28 without interfering in any way with the operation of the tempo device. This renders it possible for the operator at any time to 30 skip any desired portion of the music or to rewind and repeat at will. No claim is made for any means for operating these various devices and mechanisms, but to the combination of means in a unitary structure 35 for setting such mechanisms or devices in operation. It is not understood that this is to be used simply for tempo or rewind, but that expression devices or mechanisms may also be set in operation by the same 40 or similar means; in fact, that the entire player mechanism may be controlled and regulated by one or more unitary structures 45 that can be inconspicuously located in the front of the piano and can be entirely hidden from view when not in use.

I do not limit myself to use of my invention in player pianos or in piano players, as it can be utilized in organs and other musical instruments.

50 My invention contemplates broadly a lever or other movable member connected for in some way controlling the playing mechanism, and carrying with it means operable by the same hand for otherwise controlling 55 the said mechanism, whereby a plurality of the controlling devices essential to the me-

chanical playing of a piano or organ are contained in one bodily movable element.

I claim:

1. In a player piano, the combination with 60 a keyboard, a key slip, a movable structure comprising a plurality of controlling devices, and a pivoted plate for moving said structure parallel to said key slip and concealing said devices when not in use. 65

2. In a player piano, the combination with a keyboard, a key slip, a movable structure comprising a plurality of controlling devices, and a pivoted plate adapted when open to serve as a handle for moving said 70 structure parallel to said key slip and serving when closed as a cover to conceal it.

3. In a player piano, the combination with a keyboard, a key slip, a movable structure comprising a plurality of controlling devices, a pivoted plate adapted when open to serve as a handle for moving said structure parallel to said key slip and serving when closed as a cover to conceal it, and means 75 for locking said plate in upright position. 80

4. In a musical instrument, the combination with a key slip a movable structure comprising a plurality of controlling devices, and means mounted thereon for moving said structure parallel to said key slip 85 and for concealing it when not in use.

5. In a player piano, the combination with a key-slip, a movable structure constituting a tempo regulator, and a combined handle and cover for moving and concealing said 90 structure, pivotally mounted thereon.

6. In playing mechanism for pianos or organs, a handle moved bodily laterally from side to side to control the tempo, and controlling devices in the form of one or 95 more push-buttons movable with said handle and operable by other fingers of the same hand.

7. In a musical instrument, the combination with a key slip, a plurality of hand-operated controlling devices combined in a unitary structure, means to slide said structure parallel to said key slip for operating one of said controlling devices, and means for concealing said devices when not in use. 100 105

Signed by me at Rock Island, Illinois this 20th day of August 1909.

ROBERT J. BENNETT.
